UNITED STATES PATENT OFFICE.

JAMES A. KIRBY, OF CHICAGO, ILLINOIS, ASSIGNOR TO ERNEST S. BENSON AND GEORGE T. HOUSTON, BOTH OF SAME PLACE.

SEAL-LOCK.

SPECIFICATION forming part of Letters Patent No. 360,100, dated March 29, 1887.

Application filed September 7, 1886. Serial No. 212,949. (Model.)

To all whom it may concern:

Be it known that I, JAMES A. KIRBY, residing at Chicago, in the county of Cook and State of Illinois, and a citizen of the United States, 5 have invented a new and useful Improvement in Seal-Locks, of which the following is a full description, reference being had to the accompanying drawings, in which—

Figure 1 is an elevation showing the lock applied to a door, the full door and side not being shown, but only so much thereof as is required to show the manner of applying the lock; Fig. 2, a front elevation of the lock; Fig. 3, a longitudinal section of the lock closed 15 and the seal in place; Fig. 4, a longitudinal section with the seal cut off by the sliding bolt and the parts in position for the face-plate to be swung up; Fig. 5, a detail of the form of seal to be used with the lock of Figs. 1, 2, 3, 20 and 4; Fig. 6, a front elevation showing a modification in the construction of the sliding bolt or plate and the knife; Fig. 7, a detail in perspective, showing a modification in the form of seal to be used with the construction of lock 25 shown in Fig. 6.

This invention relates to seal-locks to be used in connection with receptacles which are to be securely locked and sealed for the purpose of disclosing any tampering with the contents; and it has for its objects to construct a lock which can be readily applied, and by which a hinged face-plate will be held securely, and which can have a seal readily applied thereto; to improve the manner of applying the seal and the means for breaking or disconnecting the same when the receptacle is to be opened; to improve the form of the seal and the manner of applying it to a lock, and to improve the construction and operation of the seal-lock as a whole; and its nature consists in the several parts and combination of parts, hereinafter described, and pointed out in the claims as new.

In the drawings, A represents a sliding bolt, 45 one end of which, in the form of the construction shown in Figs. 1, 2, 3, and 4, has a knife-edge, a.

B represents a hinged face-plate, on which is mounted the sliding bolt A, and this hinged 50 face-plate B, at one end, is provided with ears

b, for hinging the hinged face-plate B to the supporting or attaching base-plate. The face-plate B has across its face transversely a cross-piece, B', beneath which the sliding bolt A passes, and on this cross-plate B' is a loop, b', 55 for the attachment of the ordinary wire or strip seal.

C represents a slot or opening in the face-plate B, into which projects a pin, c, from the sliding bolt A, which slot C permits an end movement of said bolt for the purpose of locking and unlocking the bolt.

D represents a base-plate having therein holes d, for the passage of screws, bolts, or other devices for attaching the lock as a whole 65 in place.

E represents a head on the base-plate D, and having a part, e, to enter between the ears b, so that a pin, e', can be passed through said ears and part e and hinge the face-plate B to 70 the base-plate D.

F represents posts on the base-plate D, connected at their outer ends by the cross-pieces f, beneath which the end of the sliding bolt A passes when the lock is fastened. 75

G represents a stud on the base-plate D, between the head E and posts F, and projecting out so as to have the face-plate B, when down, come in contact with its outer end.

H represents a hasp attached to the receptacle by a staple, g, and having in its body a slot, h, to pass over the stud G. As shown, the hasp H is attached to the casing of the door and the base-plate D is attached to the door, the arrangement shown being one for 80 applying the lock to a freight or other car; but the lock is to be used with any receptacle which it is desired to have securely locked and sealed.

I represents the seal, which can be made of 90 lead or other soft material that cannot be removed without being defaced. As shown in Fig. 5, the seal I has a rivet, i, which enters an opening, j, in the face-plate B, and, as shown, the inner end of said opening is countersunk, and in line therewith on the head E is a point, k, against which the end of the rivet i will strike as the seal is forced down, and by which point k the rivet will be spread to fill the countersink of the opening j, as 100

shown in Fig. 3, so that the seal I cannot be removed, except by severing or breaking the rivet i.

The modification shown in Fig. 6, instead of having a knife-edge, a, on the end of the bolt A, has a blade, A', secured in the cross-piece B', with a knife-edge, a', which blade lies above and in contact with the face of the bolt A, and in this arrangement the seal I, instead of being carried by or secured to the plate B, is carried by or secured to the bolt A between the blade A' and the cross-piece f, when the said bolt is closed; and, instead of a single rivet i for the seal I, two rivets can be used, as shown in Fig. 7, and when two rivets are used two holes j are provided, as shown in Fig. 6. As shown in said figure, the rivets i are upset or headed by their ends striking the plate B between the slot C and the end of said plate. The bolt A in the construction shown in Fig. 6 has a turned end, A'', in which is a slot, and through which slot and the loop b' the ordinary wire or strip seal can be passed, if so desired.

25 The bolt A is slipped into place beneath the cross-piece B' on the face-plate B and the stud or pin c secured thereto in the slot C, and the plate B is hinged to the base-plate D by the pin e', when the lock is ready for use; and in 30 use the lock is attached to the receptacle by securing the plate D in place with suitable screws or other means through the holes d, and the hasp H is attached to the receptacle to have its slot h pass over the stud G. The plate B is then dropped down over the end of 35 the hasp, and the end of the bolt A is then passed under the cross-piece f, and after this is done the seal I is applied by entering the rivet or rivets i through the opening or openings j, and by spreading the end or ends of such rivet or rivets completing the sealing of the lock.

The seal, if it remains intact, shows that the receptacle has remained closed, and to unlock 45 the receptacle the bolt A is moved in the direction to withdraw its end from beneath the cross-piece f, which movement severs the neck or rivet i of the seal I, cutting off the seal and allowing the bolt A to be unobstructed in its 50 withdrawal, and when the bolt is wholly withdrawn from beneath the strip or cross-piece f the bolt A and plate B can be turned up and the hasp H removed from the stud G. The lock can be applied and used again in the same 55 manner by simply putting a new seal in the place of the one removed.

The seals are to be lettered and numbered, as usual, to indicate the party to whom they belong; and in the event it is not desired to 60 use a seal to be severed by the sliding bolt A,

the ordinary wire or strip seal can be applied by passing it through the loop b' and the slot h of the hasp, or through loop b' and the slot in the end A'' of the bolt A; or both the seal and the wire or strip seal can be used, if so desired. 65

It will be seen that with either form of construction the seal is removed through the movement of the knife-edge a, whether the seal is carried by the face-plate B or by the bolt A.

It is evident that the lock could be attached 70 to the body of the receptacle and the hasp attached to the door or cover, and the lock can be used with other forms of fastening devices than a hasp, without departing from the spirit of the invention, which is the employment of a sliding locking-bolt and a seal arranged in connection with the bolt to be severed by the movement of bolt in being released. 75

What I claim as new, and desire to secure by Letters Patent, is—

80 1. In a seal-lock, the combination, with a base-plate and a face-plate hinged thereto, of a sliding bolt, a riveted seal, and a knife-edge in proximity to or abutting against the rivet of said seal, so that said rivet is severed by the movement of the sliding bolt, substantially as described.

2. In a seal-lock, the combination, with a face-plate and a seal riveted thereto, of a sliding bolt having a knife-edge, substantially as 85 90 and for the object described.

3. In a seal-lock, the combination, with a face-plate having a seal riveted thereto and hinged to a base-plate, of a sliding bolt having a knife-edge, substantially as and for the 95 purpose described.

4. The combination, with a sliding bolt, A, having a knife-edge, and a hinged face-plate, B, having a seal riveted thereto, of the base-plate D, having a cross-piece, f, and a stud, G, 100 substantially as described.

5. A sliding bolt, A, having a knife-edge, and a hinged face-plate, B, having cross-piece B', and loop b', in combination with the base-plate D, cross-piece f, stud G, and hasp H, 105 substantially as described.

6. A sliding bolt, A, having a knife edge, and a hinged face-plate, B, in combination with the plate D, cross-piece f, stud G, hasp H, and the seal I, riveted to the face-plate B, 110 substantially as described.

7. The combination of the sliding bolt having a knife-edge and the base-plate, of the hinged face-plate having an opening for the reception of the rivet of a seal, substantially 115 as described.

JAMES A. KIRBY.
